UNITED STATES PATENT OFFICE

THOMAS E. CLARK, OF DETROIT, MICHIGAN, ASSIGNOR TO THOS. E. CLARK WIRELESS TELEGRAPH - TELEPHONE CO., OF DETROIT, MICHIGAN, A CORPORATION OF MICHIGAN.

SYSTEM FOR WIRELESS TELEGRAPHY.

No. 805,412.

Specification of Letters Patent.

Patented Nov. 21, 1905.

Application filed February 17, 1902. Serial No. 94,346.

To all whom it may concern:

Be it known that I, THOMAS E. CLARK, a citizen of the United States, residing at Detroit, in the county of Wayne, State of Michigan, have invented certain new and useful Improvements in Systems for Wireless Telegraphy; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to new and useful improvements in automatic wireless signal and telegraph apparatus, and consists in the construction and arrangement of parts hereinafter fully set forth and pointed out particularly in the claims.

The objects of my invention are to provide a system embodying a novel form of adjustable emitter or transmitter, and means for increasing the effect or force of electric waves at the transmitting-station; also, a controlling or automatic signal - sending device in connection with the oscillator driven by any suitable means, and adapted to produce at the transmitter dots and dashes in accordance with the Morse code or other system of signaling.

A further object is to provide an efficient form of coherer or receiver working in connection with a restoring mechanism at the receiving-station, adapted to receive and record the dots and dashes, or other signals, produced automatically at the transmitting-station.

The above objects are attained by the mechanism illustrated in the accompanying drawings, in which:—

Figure 1 is a diagrammatical view embodying the preferred form of arranging my apparatus at the transmitting-station. Fig. 2 is a like view showing a preferred form of arranging the apparatus embodying my invention at the receiving-station.

In the drawings two stations are represented, one comprising the transmitting apparatus and the other the receiving apparatus, but in actual practice or commercial use, both stations will be equipped with transmitting

and receiving apparatus so that signals may be sent and received at both stations.

Referring to Fig. 1, I will first describe the transmitting apparatus which comprises a Ruhmkorff coil 1, the primary winding 2 of which is energized by a suitable battery or other source of electric energy 3, and with which is connected the ordinary condenser 3^a. In circuit with the battery and the primary of the induction-coil through the line or conductor 4 is an interrupter comprising a vibrating armature 5 and the contact-screw 6, such as are ordinarily employed. In series with the battery and the primary of the induction-coil is an automatic controller, or signal apparatus, 7 operated by a small motor 8, or other suitable means, whereby a rotary motion may be imparted to the shaft 9, upon the projecting end of which is a worm 10, which meshes with the gear - wheel 11, mounted upon the shaft 12 suitably journaled and carrying a hard-rubber cylinder 13. Seated in the periphery of said cylinder are the adjustable pins 14, 15 and 16. Located in the path of the pins carried by the cylinder 13 is a contact-spring 17 connected through the binding-post 18 with battery 3 and carrying at its free end a contact-point 19. Below the contact-spring 17 is a second spring 20 carrying contact-point 21 which is directly beneath contact-point 19, said contact-spring 20 being connected through binding-post 22 and line 23 with the primary of the induction-coil, thereby completing the circuit of battery 3. Said circuit is normally open at contact-points 19 and 21. When the motor is started so as to revolve the gear-wheel 11, the cylinder 13 is rotated and the pins therein are successively caused to engage the spring-terminal 17, and force it downward so as to close the circuit at points 19 and 21, thereby rapidly closing and opening the circuit, including the primary of the induction-coil, and producing a rapidly-alternating current in the secondary winding 24 of said coil whose terminals are connected to the binding-posts 25 and 26, from which lead the current-conductors 27 and 28, in which are included the copper spheres 29 and 30. From said spheres lead the lines of the external circuit 31 and 32 connected with the aerial conductors 34 and 35 which may be corrugated metal drums. The oscillations are produced

1 rupture incident to the leaping of
ark across the air-gaps between the
spheres 29 and 30, and the interposed copper
cones 36 and 37, and between the cones them-
5 selves setting up an electrical oscillation which
is given off at the aerial conductors 34 and 35.

It will be seen that the pins of the rubber
cylinder 13 are of varying contact-surface
so as to produce a variation in the length of
10 time the points 19 and 21 remain closed. The
pin 14 will give a short impulse, like a dot,
and the pins 15 and 16 impulses of longer du-
ration, like dashes, whereby any desired sig-
nal may be arranged for by changing or re-
15 arranging the pins producing the impulses
which are given off at the transmitting-sta-
tion, and received upon the apparatus at the
receiving-station.

The copper balls of the oscillator or trans-
mitter are mounted upon vertically-movable
20 connecting-rods 40 and 41, which pass through
insulated holders 42 and 43 of hard rubber or
ebony, and in which holders said rods are ad-
justable so that the space between the spheres
25 and the interposed copper cones may be in-
creased or decreased to change the frequency
of the oscillations. In the circuit-wire 32
leading to the aerial conductor 35 is an ad-
justable inductive resistance-coil 44 wound
30 around a movable insulated core 38, whereby
the inductive effect upon the secondary may
be regulated to assist in acquiring a corre-
spondence of tuning between the transmit-
ting and receiving stations.

35 The apparatus at the receiving-station, illus-
trated in Fig. 2, comprises the aerial conduct-
tors 45 and 46 connected with conducting-
wires 47 and 48 which lead to and terminate
in the primary winding of the repeater-coil
40 53, while the secondary winding of said coil is
connected to the conductors 47^a and 48^a leading
to the binding-posts 49 and 50 that are
electrically connected with the jaws 51 and 52,
which receive the contact-terminals of the co-
45 herer or receiver. The repeater-coil is of the
familiar type of repeater-coils commonly used
in telephone-work. This coil serves to gather
the minute waves from the aerials and collect
them in a large volume in the primary, in-
50 ducing in the secondary a smaller volume but
of higher tension calculated to repeat the im-
pulse forcibly to the receiving apparatus.
Located in conductor-wire 48 of the aerial cir-
cuit is a variable inductance-coil 54 for the pur-
55 pose of regulating the length of the receiv-
ing-wire according to the tension of the elec-
trical wave or impulse, enabling a wave of
high frequency to be choked or retarded by
cutting in more resistance so as to prevent it
60 from reaching the receiver with undue force.

The coherer, or receiver, consists in a glass
tube 59 capped at its ends with hard-rubber
or ebony caps 60, which are sealed or cemented
thereon. The electrodes 64, which enter

the glass tube from opposite directions, pass 65
through the ebony caps and carry the contact-
terminals 61. The said electrodes are pref-
erably formed of highly-polished and nickel-
plated phosphor bronze and confine between
70 their adjacent faces the metallic filings 65. 70
The contact-terminals 61 are provided with
flat sides adapted to be received between the
contact-jaws 51 at each end of the coherer,
mounted upon the hard-rubber base 75, and
75 connected electrically with the binding-posts 75
49 and 50, whereby a continuity of the elec-
trical circuit between the electrodes of the co-
herer and the circuit-wires 47^a and 48^a is ef-
fected. Also connected with the binding-
posts 49 and 50 are the circuit-wires 76 and 80
77, in which is included a battery 78 and the
coils of a relay-magnet 79, which circuit is
normally open at the coherer. When an elec-
trical impulse is received at the receiving-
station, it operates to cohere the filings in the 85
receiver and close the relay-circuit between
the electrodes, thereby attracting the arma-
ture 80 and closing the circuit through the
conductor-wires 81 and 82 in which is in-
cluded the battery 83, and of which the ar-
mature 80 forms a complementary portion.
In series with the battery 83 is a vibrator, or
electric tapper 84, the hammer of which is
operated to strike the end of the screw 71 in
the end of one of the electrodes, and deco-
95 here the filings, thereby opening the relay-
circuit as soon as the impulse is received.

In the operation of the apparatus at the re-
ceiving-station, the impulses received through
the aerial conductors cause the closing of the 100
relay-circuit at the coherer, and an immediate
opening of said circuit by means of the elec-
trical tapper, whereby the dots and dashes, or
other forms of signals sent, are reproduced in
the receiving instrument, and are made mani-
fest in the electric gong 86 in series with bat-
tery 87 through conductors 88 and 89, and
105 which connect with the relay-circuit. In-
cluded in line 88 of the gong, or secondary
circuit, is a magnet 92 adapted to actuate a 110
target 93 to place it in the dotted position
shown in Fig. 2, whereby the electrical sig-
nal received in the alarm is reproduced in the
target indicating therein each impulse and its
duration, the indication of the signal in the
115 target being automatic, and the manifestation
remaining in the form of vibration as long as
each impulse lasts.

Having thus fully set forth my invention,
what I claim as new, and desire to secure by
120 Letters Patent, is—

1. In a system of wireless telegraphy and
signaling, the combination, with an aerial con-
ductor, of an induction-coil having each ter-
minal of its secondary connected with said con-
ductor through an external circuit, copper
125 spheres included in said circuit, a conical body
adjacent to but spaced from said spheres, which

BEST AVAILABLE COP^Y

3

latter are adjustable so that the space between them and the conical body may be increased or decreased.

2. In a system of wireless telegraphy and signaling, the combination, with aerial conductors, of an induction-coil having its secondary connected with said conductors by external circuits, adjustable copper spheres in said circuits, conical bodies fixedly interposed between said spheres spaced therefrom and from each other, means for adjusting the spheres to regulate the spaces between them and the conical bodies, and an adjustable inductive resistance-coil included in the circuit of the aerial conductor.

3. In a system of wireless telegraphy and signaling, the combination with an emitting-conductor, of a transmitter adapted to produce electrical oscillations, an induction-coil having its secondary connected with said oscillator, an automatic circuit-closer or signal apparatus included in the primary of said induction-coil, said circuit-closer carrying continuously-movable pins of non-conducting ma-

terial having varying engaging surfaces adapted to intermittently close the primary circuit in varying durations.

4. In a system of wireless telegraphy and signaling, the combination with a transmitter, of an automatic circuit-closer comprising a rotary cylinder having changeable non-conductive pins therein of varying engaging surfaces, a spring-terminal forming a part of an electric circuit connected with the transmitter located in the path of the pins of said cylinder, a contact-terminal immediately below the free end of said spring, whereby the circuit is closed through said spring and terminal by the engagement of the pins with the spring as the cylinder revolves, intermittently closing said circuit for periods of varying duration.

In testimony whereof I sign this specification in the presence of two witnesses.
